GAS AND AIR MIXING DEVICE

Samuel Barton Brown, Los Angeles, Calif.

Application December 5, 1932, Serial No. 645,742

5 Claims. (Cl. 48—180)

This invention relates to improvements in gas and air mixing devices for use in connection with internal combustion engines or gas furnaces, where gas and air are mixed in certain proportions for combustion.

One object of my invention is to produce a gas and air mixing device where the gas and air are broken up into a comparatively large number of fine streams upon entering the device.

10 Another object is to thoroughly mix the air and gas within the mixing chamber of the device.

A further object is to provide means for accurately proportioning the ratio of the air-gas mixture and for changing the quantity of mixture 15 passing through the device.

Other objects of the invention will appear in the following specification where I have described some forms of my invention; they may be varied or modified, however, without departing from 20 the spirit of my invention.

In the drawings forming part of this specification like reference characters denote like parts in all the figures.

Fig. 1 is a vertical section of one form of the 25 device assembled; Fig. 2 is a side elevation partly sectioned, of the housing of the device; Fig. 2a, a cross-sectional view through line A—A of Fig. 2; Fig. 3, a vertical mid-section of a modified form of air float; Fig. 4 a side elevation of the gas supply valve; Fig. 4a, a cross-section looking up from the line C—C of Fig. 4; Fig. 5, a side elevation showing separately the regulating shutter shown in Fig. 1, and Fig. 5a is a section on line B—B of Fig. 5.

35 In Fig. 1, 1 represents the housing having a cap 1a containing vacuum chamber 2, the perforations or air holes 3, the mixing chamber 4, the liquid fuel vapor supply tube 5 and the regulating shutter 6, with rod 7 attached to said shutter; 8 is the air 40 float which is raised to a greater or lesser degree by vacuum in vacuum chamber 2. The liquid fuel vapor supply tube 5 is provided with a diametrically reduced upper portion 5a having diametrically opposite groups of fuel holes 9. As said air 45 float rises it uncovers a gradually increasing number of air holes 3 and fuel holes 9 of the gas supply tube 5. Said tube is inserted into the housing sleeve 10. In operation, air float 8, to which is attached sleeve 11, which may be regarded as a reduced neck portion of said float, is raised to a greater or lesser degree, depending on the amount of vacuum in vacuum chamber 2. The housing 1 is provided with a reduced neck portion 1a and the neck portion of the float has a working fit 50 within the neck portion of the housing, while the

enlarged body portion of the float has a working fit within the diametrically engaged or body portion of the housing 1. The vacuum arises from the suction stroke of the engine piston which causes a vacuum in manifold 16, and hence in 60 mixing chamber 4, whence it communicates with vacuum chamber 2 through communicating passage 14. The greater the vacuum is in such chamber 2, the higher will such air float 8 be raised, thereby uncovering by its lower piston 17 a large

65 number of air holes 3 and fuel holes 9, and since the number and size of these holes bear a certain ratio to each other, it is evident that the operation of mixing air and gas in certain proportions for different throttle openings is automatic, depending upon the position of throttle 15 in intake manifold 16. If it is desired to change the air and gas ratio, which may be necessary at times, rod 7 is turned slightly, by handle 7a, which will turn shutter 6, thereby changing the 70 number of fuel holes and thus regulating the proportion of the mixture to any desired degree.

Owing to the fact that a multiplicity of relatively small air intake holes are provided in the housing which surrounds the fuel supply means 80 in an outwardly spaced relation thereto, a large number of fine streams of air are directed into the fuel spray in such a manner as to cause a very efficient supply of oxygen thereto. It will be seen that an annular mixing chamber is provided having centrally located therewithin a fuel supply 85 from which the fuel is directed outwardly thereby mingling with the air supply which is directed inwardly into said annular chamber.

Figs. 5 and 5a show details of the shutter 6. 90 By turning rod 7 more or less, the shutter will cover any desired number of holes 9. It is thus seen that while the vacuum in vacuum chamber 2 will automatically control the amount of air and gas by raising air float 8 to a greater or 95 lesser degree, shutter 6 permits the regulation of the air-gas ratio admitted to the mixing chamber.

This air-gas ratio may also be changed by varying the amount of air admitted through holes 3 by turning air shutter 22 to the right or to the left, which will uncover a greater or lesser number of air holes 3. The shutter 22 is held in place by a set screw 22a. Fig. 2a shows a sectional view through the air shutter 22 and the 100 holes 3 of housing 1. This air shutter may be operated by any convenient means. In order to obtain a still finer means of adjusting the amount of air admitted, as might be desirable, for instance, when the throttle is only slightly 105 110

opened or at a low engine speed, I may use a separate external auxiliary shutter 22a, to cooperate with the main external shutter 22, which is made to uncover one hole at a time or a portion 5 of a hole, by rotating said shutter to the right or to the left, as may easily be understood by looking at Fig. 1. This shutter 22a acts in a similar manner as air shutter 22 in Fig. 2a.

Fig. 3 shows a modified form of air float having 10 two sleeves 11a and 11b which regulate the amount of air and liquid fuel vapor respectively in a similar manner as 11 of circular air float 8, shown in Fig. 1. If air float 8 is in its lowest position, a shoulder or a ground or finished surface 18 will come into contact with a similar 15 surface at the bottom of the air float, thereby effectively cutting off the flow of gas or liquid fuel vapor. For example, if the device is used in connection with an internal combustion engine, and illuminating gas or natural gas, as 20 furnished in gas mains, is used as fuel, when the engine is stopped, the air float would drop and prevent the waste of gas.

In practice, if the device is used with an internal combustion engine, pipe 23 is attached to 25 the gas supply. The gas will enter fuel chamber 5a but, the engine being at rest, it will be prevented from flowing into mixing chamber 4, because the air float 8 is in its lowest position, 30 thus shutting off communication between holes 9 and mixing chamber 4. As soon as the engine is started, suction will be created in the manifold, which suction is communicated to mixing chamber 4 and vacuum chamber 2. Air float 8 35 will be raised in proportion to the vacuum existing within such vacuum chamber, thereby uncovering a certain number of air holes and vapor holes, the air and vapor will rush through such holes intimately mixing with each other within 40 the mixing chamber 4 and then flowing in a mixed state through manifold 16 into the engine, not shown.

25 represents an air cleaner to filter the air which enters the device. This may consist of 45 wire gauze and cloth or any other type of air filtering medium as may be found desirable. As air cleaners and their attachments to carburetors or fuel mixing devices are well known in the art, I do not think it necessary to here describe such 50 cleaners or their attachments to the device in detail.

Having now described my invention, what I claim as new and desire to protect by Letters Patent is:

55 1. In a device of the kind described, a cylindrical housing having a mixing chamber there-
within, means to supply fuel to said mixing cham-
ber, said housing having a multiplicity of air inlet
openings through the side thereof, a main exter-
nal shutter mounted upon said housing and hav-
ing a rotational adjustment thereon to simul-
taneously uncover a plurality of the air intake
openings thereof, and an auxiliary external shutter
having a rotational adjustment upon said 65 housing to uncover air inlets thereof one at a
time.

2. In a device of the kind described, a tubular liquid fuel vapor supply member having a multi-
plicity of liquid fuel vapor supply openings
through the side thereof, a shutter having a
working fit within said tubular member and ro-
tatably adjustable therewithin to regulate the
liquid fuel vapor supply, a housing having a

mixing chamber surrounding said tubular mem-
ber, said mixing chamber being in communica-
tion with said liquid fuel vapor supply, and means
controllable by suction to supply air through the
wall of said housing to said mixing chamber.

3. A gas mixing device for mixing liquid fuel vapor and air in definite proportions consisting of a cylindrical housing having a body portion and a diametrically reduced neck portion of less diameter than said body portion, a circular float having also a body portion and a diametrically reduced neck portion, the body portion of said float having a working fit within the body of said housing, and the neck portion of said float having a working fit within the neck portion of said housing, there being within the neck portion of said housing a multiplicity of air intake open-
ings which are regulated by the position of the neck portion of said float, a tubular liquid fuel vapor supply member projecting into the neck portion of said float and having also a multiplicity of fuel supply openings which are controlled by the position of the neck portion of said float, there being within the neck portion of said housing an annular mixing chamber between said tubular member and said housing, and a suction pipe communicating with said housing through said mixing chamber and also communicating with a vacuum chamber within said housing to operate said float.

4. A gas mixing device for mixing liquid fuel vapor and air in definite proportions consisting of a cylindrical housing having a body portion and a diametrically reduced neck portion of less diameter than said body portion, a circular float having also a body portion and a diametrically reduced neck portion, the body portion of said float having a working fit within the body of said housing and the neck portion of said float having a working fit within the neck portion of said housing, there being within the neck portion of said housing a multiplicity of air intake open-
ings which are regulated by the position of the neck portion of said float, a tubular liquid fuel vapor supply member projecting into the neck portion of said float and having also a multiplicity of fuel supply openings which are controlled by the position of the neck portion of said float, there being within the neck portion of said housing an annular mixing chamber between said tubular member and said housing, and a suction pipe communicating with said housing through said mixing chamber, there being a vacuum chamber in the body portion of said housing and an air passage leading from said mixing chamber through the neck portion of said float to said vacuum chamber.

5. A gas mixing device for mixing liquid fuel vapor and air in definite proportions consisting of a cylindrical housing having a multiplicity of air inlets through the wall thereof, a float provided with a sleeve portion having a working fit within said housing to control the amount of air intake therethrough, said float being adapted to have its movements controlled by suction, a liquid fuel vapor supply tube projecting into the cylindrical portion of said float, said tube having a multi-
plicity of liquid fuel vapor supply openings con-
trolled by the position of said float, there being an annular mixing chamber between said tube and housing, and a cylindrical shutter having a working fit within said tube and rotationally ad-
justable to control the amount of liquid fuel vapor supply.

S. BARTON BROWN.
